Primary Examiner — Jasmine Mlinarcik

(57) **CLAIM**

The ornamental design for a hat, as shown and described.

DESCRIPTION

FIG. 1 is a front view of a hat showing my new design; FIG. 2 is a rear view of the hat; FIG. 3 is a right side view of the hat; FIG. 4 is a left side view of the hat; FIG. 5 is a top view of the hat; FIG. 6 is a bottom view of the hat; FIG. 7 is a top front side perspective view of the hat; and, FIG. 8 is a bottom front side perspective view of the hat. The broken lines in the drawing figures are illustrative of stitching forming part of the claimed design.
